CLAIM

The ornamental design for an excavator, as shown and described.

DESCRIPTION

FIG. 1 is a front perspective view of an excavator showing the new design;

FIG. 2 is a top view of the invention illustrated in FIG. 1; FIG. 3 is a bottom view of the invention illustrated in FIG. 1;

FIG. 4 is a front view of the invention illustrated in FIG. 1; FIG. 5 is a rear view of the invention illustrated in FIG. 1; FIG. 6 is a right side view of the invention illustrated in FIG. 1; and,

FIG. 7 is a left side view of the invention illustrated in FIG. 1.

The broken lines in the drawings depict portions of the excavator and form no part of the claimed design.
